DESIGN FOR A CARPET OR SIMILAR ARTICLE

Frank A. Haas, New York, N. Y.

Application July 25, 1940, Serial No. 93,919

Term of patent 7 years

To all whom it may concern:

Be it known that I, Frank A. Haas, a citizen of the United States of America, residing in New York city, in the Borough of Manhattan, county and State of New York, have invented a new, original, and ornamental Design for a Carpet or Similar Article, of which the following is a specification, reference being had to the accompanying drawing, forming part thereof, wherein,

I claim:

The ornamental design for a carpet or similar article, as shown.

FRANK A. HAAS.
